COMBINED CONFECTION MOLD AND PACKAGING TRAY

Fred Passaglia, Chicago, Ill., assignor to Sugarless Candy Corporation of America, Chicago, Ill., a corporation of Illinois

Filed Sept. 15, 1965, Ser. No. 86,997

Term of patent 14 years

(Cl. D44—1)

FIG. 1

FIG. 2

FIG. 3

FIGURE 1 is a perspective view of a combined confection mold and packaging tray showing my new design;

I claim:

The ornamental design for a combined confection mold and packaging tray, substantially as shown.
